Primary Examiner — Elizabeth A. Albert(74) *Attorney, Agent, or Firm* — Robert W. J. Usher(57) **CLAIM**

The ornamental design for a vase lamp, as shown and described.

DESCRIPTION

FIG. 1 is a side elevational view of a vase lamp showing my new design, the opposite side view being identical to the side shown;

FIG. 2 is a top perspective view thereof;

FIG. 3 is a top plan view thereof; and,

FIG. 4 is a bottom perspective view thereof, rotated through 45 degrees from the preceding view.

The broken lines in FIGS. 1–4 are included for the purpose of illustrating features on the vase lamp that form no part of the claimed design.
